UNITED STATES PATENT OFFICE.

ELMER DINGMAN, OF MICHIGAN CITY, INDIANA.

MILK-BOTTLE CLOSURE.

Application filed March 8, 1921. Serial No. 450,572.

To all whom it may concern:

Be it known that ELMER DINGMAN, a citizen of the United States of America, residing at Michigan City, in the county of La-
5 porte and State of Indiana, has invented new and useful Improvements in Milk-Bottle Closures, of which the following is a specification.

The object of the invention is to provide
10 a simple, inexpensive and efficient milk bot-
tles closure or cap adapted for attachment to
a receptacle of the type indicated regardless
of the special construction thereof as a
means of housing and protecting the mouth
15 of the receptacle against accumulations of
dust and dirt and contamination by han-
dling as by the agencies entrusted with the
service of the milk to the customers, to the
end that the lack of care of the consumer in
20 cleansing the mouth of the bottle before re-
moving the contents thereof may not result
in the contamination of the milk or the in-
troduction of germs thereinto; and with this
object in view the invention consists in a
25 construction and combination of parts of
which a preferred embodiment is shown in the
accompanying drawings, wherein:—

Figure 1 is a side view of a cap or closure
embodying the invention applied in the op-
30 erative position to a milk bottle or jar of the
ordinary or commercial form.

Figure 2 is a sectional view of the cap.

Figure 3 is a cross sectional view of the
same on the plane indicated by the line 3—3
35 of Figure 2.

The device consists essentially of a cylind-
rical cap 10, of a diameter adapting it to
40 pass freely over the ordinarily flanged
mouth or lip of a bottle 11 of the com-
mercial type, a spring retainer 12 being ar-
ranged within the cap as by being attached
by rivets 13 or the equivalents thereof to the
45 top or upper wall of the same and having
an offset 14 for fitting over the lip which is
indicated in dotted lines in Figure 2 at 15
to the end that said retainer extends under
the lip and thus yieldingly opposes the re-
moval of the cap from the bottle neck to an
extent sufficient to permit of the carrying of
50 the bottle by means of the cap as they are

ordinarily carried by the neck when deliv-
ered to the consumer.

The retainer arm in the construction illus-
trated consists of a spring tongue or strip
which is outwardly deflected near its free 55
end, as shown at 16, to provide for its ready
engagement with the mouth of a bottle
whereupon a camming action is effected to
deflect the retainer and to permit the en-
trance of the lip or bead at the top of the 60
mouth reaching the offset portion 14, after
which the greater part of the length of the
retainer lies against the bottle and below
the bead. A corresponding action takes
place in the removal of the cap from the bot- 65
tles but in this instance the lower part of the
offset portion 14, passing over the body
springs the retainer outwardly so that it
may be readily removed. The resistance to
removal, however, is sufficient to enable the 70
bottle with its contents to be carried by
grasping the exterior surface of the cap.

Also preferably the extremity of the re-
tainer is extended through an opening 17 in
the wall of the cap to form a finger hold 18 75
which may be used to ease the retainer over
the lip of the bottle either in applying or
removing the same, in the event that the re-
sistance of the spring should be excessive.

Inasmuch as the device serves as a com-
plete sanitary housing for the lip of the bot-
tles the pouring of the contents from the lat-
ter by the consumer will not involve the risk
of contamination of the contents which has
been found a prevalent cause of disseminat- 80
ing diseases, and will insure the reception
by the consumer of the milk in proper con-
dition for use with safety, without involv-
ing the dealer in any inconvenience or ne-
cessitating any change in the method of han- 85
dling the bottles.

Having described the invention, what is
claimed as new and useful is:—

A central closure for milk bottles and the
like consisting of a cap for receiving and 95
housing the neck portion of the bottle, and
an interior yielding tongue for engaging the
lip or bead of the bottle, said retainer con-
sisting of a flat strip of spring material
having a portion secured to the inner face 100

of the top of the cap, an offset portion embracing the rim or bead of the bottle mouth, a lower deflected portion for initially engaging the bottle mouth to impart lateral movement to the retainer, that portion of the retainer between the deflected portion and the offset portion lying against the neck of the

bottle, and a terminal finger hold protruding through the opening in the side of the cap and adapted for imparting lateral movement to the retainer to permit removal of the cap.
